AUTOMOBILE FENDER LIGHT MARKER

A. Robert Bernstein, 14 Eastwood Lane,
Easton, Conn. 06425

Filed July 18, 1969, Ser. No. 18,271

Term of patent 14 years

Int. Cl. D12—99

U.S. Cl. D48—32

Fig. 2

Fig. 3

Fig. 4

Fig. 5

FIG. 1 is a side elevational view of an automobile fender light marker showing my new design;

FIG. 2 is a rear elevational view thereof;

FIG. 3 is a front elevational view thereof;

FIG. 4 is a front end view thereof; and

FIG. 5 is a rear end view thereof.

I claim:

The ornamental design for an automobile fender light marker, as shown.
